UNITED STATES PATENT OFFICE.

EDWARD F. KUNATH, OF JERSEY CITY, NEW JERSEY, ASSIGNOR TO
UNDERWOOD TYPEWRITER COMPANY, OF NEW YORK, N. Y., A
CORPORATION OF NEW JERSEY.

TYPE-WRITING MACHINE

No. 833,227.

Specification of Letters Patent.

Patented Oct. 16, 1906.

Application filed October 27, 1905, Serial No. 284,691.

To all whom it may concern:

Be it known that I, EDWARD F. KUNATH, a citizen of the United States, residing in Jersey City, in the county of Hudson and State 5 of New Jersey, have invented certain new and useful Improvements in Type-Writing Machines, of which the following is a specification.

This invention relates to the ribbon mechanism of type-writing machines, and particularly to means for bringing into use different colors of ribbon at will.

I provide two or more separate ribbons of different colors and movable independently 15 of one another to cover the printing-point. In the preferred form of the invention the ribbons are superposed or placed one in front of another in front of the platen and means are provided for causing either ribbon to 20 cover and uncover the printing-point during the type-strokes, while the other ribbon remains idle.

I illustrate my invention as applied to the well-known "Underwood" front-strike writing-machine, in which spools carrying the usual ribbon are mounted upon vertical axes one at each side of the printing-point in front of the platen. Behind said ribbon I stretch a short ribbon of red or other special color, 25 which is wound by means of spools placed at the extreme sides of the machine. The short special ribbon may in some cases be endless, and in such a case two other spools are placed at the front of the machine, so 30 that the endless ribbon winds around four spools and incloses the usual ribbon and its spools. Winding means are provided for the endless ribbon, and I also provide an individual carrier or vibrator for each ribbon—one 35 carrier in front of the other. Said carriers are shown movable up and down by means of levers. The latter may be substantially like those commonly used in the Underwood machine and may be mounted side by side, 40 either lever being called into operation at the type-strokes. The lever-operating mechanism includes the usual universal-bar frame, which reciprocates at each type-stroke. Upon said reciprocating member I mount 45 50 actuators, one for each of said ribbon-vibrating levers, said actuators being shiftable to engage either one or the other lever. Means

are provided for detaining the actuators in either shift position.

In the accompanying drawings, Figure 1 55 is a perspective view illustrating my invention applied to an Underwood front-strike writing-machine. Fig. 2 is a perspective view of the duplex ribbon-actuator. Fig. 3 is a sectional elevation of the machine, taken 60 from front to rear.

Upon the front side of a revoluble platen 1 strike types 2, mounted upon type-bars 3, the latter being operated by upright levers 4, connected to key-levers 5. In front of the 65 platen is the usual ribbon 6, winding back and forth upon spools 7 8, the latter mounted on vertical shafts 9 10, provided with pinions 11, meshing with pinions 12, the latter rigidly connected to ratchet-wheels 13, operated by 70 pawls 14, the latter pivoted upon rock-arms 15, fixed upon a rock-shaft 16, having an arm 17, and engaging with the latter is a rock-arm 18, extending forwardly from an upright rocking frame 19, to which is pivoted 75 at 20 ears formed upon the rear end of a horizontal table or reciprocating frame 21, the latter having fixed upon its front portion a segmental universal bar 22 engaging the type-bars. As so far described the parts are in 80 common use upon said Underwood machine. Said ribbon 6 is threaded through an up-standing carrier 23, loosely pivoted at 24 to the front end of a lever 25, which is pivoted upon a shoulder-screw 26, the latter threaded 85 into a bracket 27, fixed upon the rear side of a horizontal shift-rail 28. Said lever 25 has an arm 29 extending up from said pivot 26 and provided with a laterally-projecting pin 30, whereby the lever is operated during the 90 backward-and-forward movement of said universal-bar frame 21 in a manner presently to be explained.

In rear of the main ribbon 6 I stretch a supplemental ribbon 31, of red or other 95 special color, which extends between spools 32 33, pivoted at the extreme sides of the machine, so that the spools 7 8 lie between said spools 32 33. The latter, it will be understood, may be of any usual or ordinary type 100 and may be provided with any suitable or ordinary mechanism for winding the ribbon back and forth between them independently of the spools 7 8. Since, however, the special

ribbon is infrequently used, it is not always necessary to provide a long ribbon, and for convenience I illustrate in this instance a short ribbon, which I make endless. Spools 34 35 are mounted in front of the spools 7 8 and the ribbon 31 is carried therearound, as seen at Fig. 1, so that said ribbon 31 completely encloses or surrounds the spools 7 8 with their attached ribbon 6. The ribbon 31 will be kept taut by means of a spring 35, which is connected at one end to a fixture and at the other end to a lever 36, upon which the spool 34 is pivoted, so that the latter is forced out or in ^{the} direction to tighten the ribbon 31. The special ribbon may be caused to feed back and forth by means of a bevel-pinion 37 on the spool-shaft 9, meshing with a bevel-gear 38 upon a horizontal shaft 39, which is connected by bevel-pinions 39^a and 32^a with the spool 32. During the winding of the spool 7 the spool 32 is caused to rotate in one direction, while during the unwinding of spool 7 the spool 32 is turned in the opposite direction. It will be understood that spool 33 will be connected to spool-shaft 10 in case it is desired not to use an endless ribbon, but to coil the ribbon back and forth upon the spools 32 and 33.

The ribbon 31 is threaded through a ribbon-carrier 40, mounted directly behind the carrier 23 and having ears 41 to embrace a fixed vertical guide 42, which in said machine is the type-guiding post. Said ears 41, it will be understood, also confine the carrier 23 against lateral displacement. The ribbon-carriers are guided between said type-post 42 and a fixed abutment 43, a spring 44 being provided upon the carrier 40 for pressing both carriers lightly forward against said post 42. The carrier 40 is pivoted at its lower end to a lever 45, similar to the lever 25 and alongside thereof and pivoted upon the shoulder 26 and having an upwardly-extended arm 46, provided with a projecting pin 47, whereby it is operated.

It will be seen that the ribbon-guiding pins 40^a of the carrier 40 are set in line with the forked main portion of said carrier to correspond with the direction taken by the ribbon 51, which extends substantially straight across the machine, while the pins 23^a of the front carrier 23 are set forward of the fork of said carrier to correspond with the forward and outward direction taken by the ribbon of the spools 7 8. The pins 40^a are thus well separated from the pins 23^a, and the carriers move freely up and down independently of one another.

Upon an upstanding bracket 48, secured upon the table 21 by means of screws 49, I mount a pair of similar actuators 50 51, having deep vertical slots 52 53 to engage, respectively, the projecting lever-pins 47 30. Said actuators are preferably integral, being formed upon the ends of a vertical plate 54,

shiftable along the bracket 48 and being held upon said plate by shoulder-screws 55, which are inserted with a horizontal slot 56 in said vertical plate 54, said slot enabling the actuators to be shifted or adjusted horizontally across the reciprocating table 21, whereby either actuator 50 or 51 may engage its associated lever-pin 47 or 30, so as to vibrate either lever 45 or 25, and hence to throw up either ribbon 31 or 6 to cause the same to cover the printing-point during the operation of the types, while the other ribbon remains idle. At Fig. 1 the actuator 50 is shown in engagement with the lever-pin 47, and the lever is elevated. The arm 29 of the other lever rests against a stop 57, fixed upon the shift-rail 58, said stop serving for both levers when they are idle.

The necessary shifting of the actuators is effected by a link 59, pivoted at 60 to an ear 85 formed upon the actuator member and extending toward the right-hand side of the machine, being there pivoted at 61 to a bell-crank 62 and vibrating idly about said pivot 61 during the backward and forward reciprocations of the table 21. From the bell-crank extends forwardly a link 63 to a finger-lever or bell-crank 64, mounted at the front of the machine over the keyboard. By raising the lever 64 the link 63 is thrown back, the bell-crank 62 vibrates, the link 59 is thrown to the left, the actuator 50 is shifted out of engagement with the pin 47, and the actuator 51 is shifted into engagement with the pin 30, so that the lever 25 will thereafter be vibrated during the type-strokes and the ribbon 6 thrown up to cover the printing-point, while the ribbon 31 remains idle. To maintain the actuators in either position, I provide a spring-detent 65 upon the framework 66 to engage notches 67, formed upon the bell-crank 62.

It is usual in said Underwood machine to shift the platen up, as at 1^a, Fig. 3, to enable the upper-case characters to print. For this purpose a shifting frame is provided, of which the shift-rail 28 forms a part. The platen 1 is journaled upon a platen-frame, (not shown,) which has a roll 68 to run upon said shift-rail 28. The latter is shifted up to 115 28^a, Fig. 3, at the case-shifting operation, and with it rise the bracket 27, the levers 25 and 45, and the ribbon-carriers 23 and 40, together with the ribbons carried thereby, the deep vertical slots 52 and 53 in the ribbon-actuators accommodating the up-and-down shift movement of the lever-pins 47 30. Thus the operation of causing either ribbon to cover the printing-point at the type-strokes is carried on the same whether the 120 platen is shifted up or down.

Having thus described my invention, I claim—

1. In a type-writing machine comprising type-operating keys, and a universal bar con- 130

trolled by said keys, the combination with means for enabling the universal bar to vibrate a plurality of ribbons to cover the printing-point, of means for enabling the operator to silence either ribbon and cause the universal bar to vibrate the other ribbon, at will.

2. In a type-writing machine comprising type-operating keys, and a universal bar operated by said keys, the combination with means for winding a plurality of separate ink-ribbons, of means for enabling said universal bar to move either of said ribbons to cover and uncover the printing-point independently of the other ribbon.

3. In a type-writing machine comprising type-operating keys, and a universal bar controlled by said keys, the combination of a plurality of sets of ribbon-spools so placed that the ribbon carried by one set of spools is normally superposed near the printing-point by the ribbon carried by the other set of spools, and means adjustable by the operator for causing said universal bar to move either of said ribbons to cover the printing-point, while the other ribbon remains motionless.

4. In a type-writing machine comprising type-operating keys, and a universal bar controlled by said keys, the combination with means for supporting ribbons so that they lie in superposed relation near the printing-point, of means for enabling said universal bar to move either ribbon independently of the other to cover and uncover the printing-point at the type-strokes.

5. In a type-writing machine comprising type-operating keys, and a universal bar controlled by said keys, the combination of a pair of ribbon-carriers, and means for causing either carrier to be operated by said universal bar while the other carrier remains idle.

6. In a type-writing machine comprising a platen, types striking rearwardly against the platen, keys for operating said types, and a universal bar controlled by said keys, the combination of a plurality of ribbon-carriers mounted in front of said platen, and means controlled by a part which is adjustable by the operator for causing said universal bar to move either carrier up to the printing-point independently of the other carrier.

7. In a type-writing machine comprising a platen, types striking rearwardly against the platen, keys for operating said types, and a universal bar controlled by said keys, the combination of a plurality of ribbon-carriers mounted one in front of the other in front of the platen, and means for enabling the universal bar to cause either carrier to cover and uncover the printing-point while the other carrier remains idle.

8. In a type-writing machine comprising a set of types, and a member which reciprocates at the strokes of all the types, the com-

bination of a plurality of ribbon-carriers, and means for operatively connecting either of said ribbon-carriers to said reciprocating member, at will.

9. In a type-writing machine comprising a set of types, and a member which reciprocates at the strokes of all the types, the combination of a plurality of ribbon-carriers, and means for operatively connecting either of said ribbon-carriers to said reciprocating member, at will, and simultaneously disconnecting the other of said ribbon-carriers from said reciprocating member.

10. In a type-writing machine comprising a set of types, and a member reciprocating at the strokes of all the types, the combination of means for supporting a plurality of ribbons, a plurality of ribbon-carriers, a plurality of levers for operating said carriers, and means for connecting said reciprocating member to either of said levers, and simultaneously disconnecting it from the other of said levers, at will.

11. In a type-writing machine comprising a platen, a set of types mounted to strike against the front thereof, and a member reciprocating at the strokes of all the types, the combination of means for supporting in front of the platen, a plurality of ribbons one in front of the other, a plurality of ribbon-carriers one in front of the other and both in front of the platen, a pair of independently-operable levers mounted side by side and connected to said carriers, and means for causing said reciprocating member to operate either of said levers, at will.

12. In a front-strike writing-machine, the combination with a platen and types mounted to strike upon the front side thereof, of a plurality of ribbon-carriers one in front of the other and in front of the platen, ears upon one of said carriers, a fixed vertical guide embraced by said ears, the other carrier being between and guided by said ears, a pair of front and rear fixed vertical guides between which said carriers are mounted, a spring-finger mounted between the rear carrier and the rear fixed guide, a member reciprocating at the type-strokes, levers extending from said carriers to said reciprocating member, and means for enabling the latter to operate either lever at will.

13. In a type-writing machine, the combination with a plurality of ribbon-carriers, for vibrating ribbons to cover and uncover the printing-point, of a member reciprocating at the type-strokes, a pair of actuators mounted upon said reciprocating member, one for operating each of said ribbon-carriers, and means for rendering either actuator effective while the other is idle.

14. In a type-writing machine, the combination with types and a platen, of a plurality of ribbon-carriers, a member reciprocating at the type-strokes, and an actuator upon said

- reciprocating member and provided with a pair of members for operating both of said ribbon-carriers, and means for adjusting said actuator so as to bring either carrier into use and simultaneously silence the other carrier. 5
15. In a type-writing machine, the combination with types and a platen, of a plurality of ribbon-vibrating devices each including a projecting pin, a member reciprocating at the type-strokes, and an actuator upon said reciprocating member and provided with openings for said pins and adjustable so that one opening may engage one pin thereby to actuate the corresponding ribbon-vibrator, 15 while the other opening is out of engagement with the other pin. 20
16. In a type-writing machine, the combination with types and a platen, of a plurality of ribbon-vibrating levers having projecting pins, a member reciprocating at the type-strokes, an actuator mounted upon said reciprocating member and having openings for engaging said pins one at a time, means for adjusting said actuator, and means for detaining it in engagement with either of said pins. 25
17. In a type-writing machine, the combination with types and a platen, of a plurality of ribbon-carriers, levers connected to said carriers, a member reciprocating at the type-strokes, actuators mounted upon said reciprocating member and connectible to either of said levers at will, a finger-piece mounted upon the framework of the machine, means connecting said finger-piece to said actuators, and means for detaining said actuators in position for operating either one or the other of said levers. 30
18. In a type-writing machine, the combination with types and a platen, of a plurality of ribbon-carriers, levers connected to said carriers, a member reciprocating at the type-strokes, actuators mounted upon said reciprocating member and connectible to either of said levers at will, a link connected to said actuators, a bell-crank mounted upon the framework and connected to said link, a finger-lever near the keyboard, a link connecting said bell-crank to said finger-lever, and a 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
- carriers mounted in front of the platen between the spools in the second pair, and means for enabling said reciprocating member to effect upward movement of either ribbon-carrier while the other ribbon-carrier remains idle. 65
20. In a type-writing machine comprising a set of types, and a member reciprocating at the strokes of all the types, the combination of two pair of ribbon-spools, means for winding the ribbons upon both pairs of spools, and means for enabling said reciprocating member to cause either ribbon to be vibrated to cover the printing-point while the other ribbon remains idle. 70
21. In a type-writing machine, the combination with a platen and types mounted to strike upon the front thereof, of a pair of ribbon-spools in front of the platen, a regular ribbon thereon, spool-winding means, an endless special ribbon, and spools whereon said endless ribbon runs, the whole being constructed and arranged so that the endless ribbon surrounds the regular ribbon and its spools; and means for bringing either ribbon into use at will. 80
22. In a type-writing machine, the combination with a platen and types mounted to strike upon the front thereof, of a pair of ribbon-spools in front of the platen, a regular ribbon thereon, spool-winding means, an endless special ribbon, a second pair of spools in front of the platen over which said endless ribbon runs, the first pair being mounted between the second pair of spools, guide-spools for said endless ribbon in front of the first pair of spools, and means for bringing either ribbon into use at will. 90
23. In a type-writing machine, the combination with a platen and types mounted to strike upon the front thereof, of a pair of ribbon-spools in front of the platen, a regular ribbon thereon, spool-winding means, an endless special ribbon, a second pair of spools in front of the platen over which said endless ribbon runs, the first pair being mounted between the spools of the second pair, guide-spools for said endless ribbon in front of the first pair of spools; one of said endless-ribbon spools being mounted upon a lever which is pivoted upon the framework and provided with a spring whereby the endless ribbon is kept taut; and means for bringing either ribbon into use at will. 100
24. In a type-writing machine, the combination with a platen and types mounted to strike upon the front thereof, of a pair of ribbon-spools in front of the platen, a regular ribbon thereon, spool-winding means, an endless special ribbon, and spools whereon said endless ribbon runs, the whole being so constructed and arranged that the endless ribbon surrounds said pair of spools; a gear connecting one of said pair of spools to one of the 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
- relation past the printing-point, two ribbon- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935

spools carrying the endless ribbon; and means for bringing either ribbon into use at will.

25. In a type-writing machine, the combination with a platen and types mounted to strike upon the front thereof, of a pair of ribbon-carriers in front of the platen, means for causing either carrier to move up or down at the type-strokes while the other carrier remains idle, a pair of spools one at either side of the first-mentioned pair and in front of the platen, and means coöperating with the last-mentioned spools to support an endless ribbon.
- 15 26. In a type-writing machine, provided with a platen, platen-shifting means, types and a key-controlled universal bar, the combination with means for carrying a plurality of ribbons, of means for causing said ribbons to shift with the platen, and adjustable means for causing said universal bar to cover the printing-point with either ribbon at the type-strokes, at will, while the other ribbon remains idle.
- 25 27. In a type-writing machine, provided with a platen, platen-shifting means and types, the combination with a plurality of ribbon-carriers, of means connected to the platen-shifting means for causing said carriers to shift with the platen, and means for causing either of said carriers to cover or uncover the printing-point during the type-strokes while the other of said carriers remains idle.
- 35 28. In a type-writing machine provided with a platen, a shiftable platen-frame, and types, the combination of a plurality of ribbon-vibrating devices including parts mounted upon said platen-shifting frame, and means for causing either of said vibrating devices to operate at the operation of the types while the other of said vibrating devices remains idle.
- 40 29. In a type-writing machine provided with a platen, a shiftable platen-frame, and types, the combination of a plurality of levers pivoted upon said shiftable frame, a frame mounted to reciprocate at the type-strokes, actuators mounted upon said reciprocating frame and shiftable so as to operate either one or the other of said levers, and ribbon-carriers operable by said levers.

EDWARD F. KUNATH.
